US00D554079S

(12) **United States Design Patent** (10) Patent No.: **US D554,079 S**
Obata (45) Date of Patent: **** Oct. 30, 2007**

(54) **REMOTE CONTROLLER**

JP D1239450 S 5/2005

(75) Inventor: **Shinichi Obata**, Tokyo (JP)

(73) Assignee: **Sony Corporation**, Tokyo (JP)

(**) Term: **14 Years**

(21) Appl. No.: **29/256,389**

(22) Filed: **Mar. 21, 2006**

(51) LOC (8) Cl. **13-03**

(52) U.S. Cl. **D13/168**

(58) **Field of Classification Search** D13/168;
